CLAIM

The ornamental design for a hairbrush with a plate to remove hair from the bristles, as shown and described.

DESCRIPTION

FIG. 1 is a perspective view of the hairbrush with a plate to remove hair from the bristles embodying the design of the present invention;

FIG. 2 is a front elevational view thereof, the rear being a mirror image of the front shown in FIG. 2;

FIG. 3 is an end elevational view thereof;

FIG. 4 is an end elevational view thereof;

FIG. 5 is a top plan view thereof;

FIG. 6 is a bottom plan view thereof; and,

FIG. 7 is a bottom perspective view thereof.

FIG. 1

FIG. 2

FIG. 3
